THEODORE SCHREPPEL, OF NEW YORK, N. Y.

DESIGN FOR THE ORNAMENTATION OF PICTURE-FRAME

Design No. 16,028, dated April 7, 1885.

D16028

6248

UNITED STATES PATENT OFFICE.

THEODORE SCHREPPÉL, OF NEW YORK, N. Y.

DESIGN FOR THE ORNAMENTATION OF PICTURE-FRAME

SPECIFICATION forming part of Design No. 16,028, dated April 7, 1885.

Application filed February 20, 1885. Term of patent 3½ years.

To all whom it may concern:

Be it known that I, THEODORE SCHREPPÉL, of the city of New York, county and State of New York, have invented and produced a new and original Design for the Ornamentation of Picture-Frames, of which the following is a full and exact description, reference being had to the accompanying photograph, forming a part hereof.

10 The accompanying photograph represents a face view of my new design for the ornamentation of picture-frames.

In the accompanying photograph, A represents the design ornamenting the sides of the 15 picture-frame, and B B the corner-pieces.

The design A is composed of a stag's head, underneath which is a crown, the whole partly

surrounded by a wreath of laurel leave, the bottom and extending upward toward the corner, outside of the laurel wreath, sprays of oak leaves, one each side of the wreath. The pieces B B consist of the representation of a sheep or lamb resting on crossed shepherds' crooks.

I claim—

The design for the ornamentation of frames, consisting of the piece A and the corner-pieces B B, having the ornamentation substantially as shown.

THEODORE SCHREPPÉL
